COMBINED MOLDED WALL FASTENER AND HOOK

Alan J. Solo, Brooklyn, N.Y., assignor to Knock-N-Lok
International, Inc., Brooklyn, N.Y.

Filed Dec. 12, 1974, Ser. No. 532,201

Term of patent 14 years

Int. Cl. D8—08

U.S. CL. D8—271

FIG. 1 is a perspective view of a combined molded wall fastener and hook showing my new design;

FIG. 2 is a top plan view;

FIG. 3 is a front elevational view;

FIG. 4 is a right side elevational view;

FIG. 5 is a rear elevational view; and

FIG. 6 is a bottom plan view.

I claim:

The ornamental design for a combined molded wall fastener and hook, substantially as shown.
